SOUND WAVE TRANSDUCER

Leslie J. Anderson, Moorestown, N. J., assignor to
 Radio Corporation of America, a corporation
 of Delaware

Application June 30, 1949, Serial No. 102,228

7 Claims. (Cl. 313—146)

1

My invention relates to improvements in sound wave transducers, and particularly to an improved frequency sensitive sound wave transducer in the form of an electronic tube.

There are many instances in which sound waves, and particularly so-called ultrasonic (high frequency sound) waves, are extremely useful for industrial and military applications. For example, systems are well known for transmitting intelligence by means of modulated sound waves, for detecting obstacles by means of reflected sound waves, and the like. In such systems, it is customary to provide a transducer at the point of wave reception which will convert the sound waves into electrical energy for more convenient handling from the standpoint of amplification and the like. Usually, it is also necessary to provide some kind of mechanical or electrical filtering system in order to separate the desired sound waves from other interfering waves. Such electrical and/or mechanical filters are often relatively complex to design and manufacture, and represent an additional item to complicate the apparatus.

It is a principal object of my invention to provide an improved transducer for converting sound waves of predetermined frequency into electrical energy.

Another object of my invention is to provide a combined filter and sound wave transducer.

Another object of my invention is to provide a novel electronic tube.

According to my invention, the foregoing and other objects and advantages are attained by mounting a so-called free-free bar in one wall of an electronic tube envelope so that one of the free bar ends can serve as one of the tube electrodes. The term "free-free bar" is used herein and in the appended claims to designate an elongated, vibratory element supported approximately at its center and adapted to vibrate transversely at a frequency determined by the bar dimensions with a nodal point at the bar center and antinodal points at or near the bar ends when either bar end is set in motion transversely. By mounting such a bar in the tube envelope wall as described, the electron stream in the tube will be subject to variation due to variations in the spacing being the "bar" electrode and the other tube electrode or electrodes. The bar will vibrate in response to sound waves of predetermined frequency impinging on the free bar end outside the tube envelope.

A more complete understanding of the invention can be had by reference to the following

2

description of illustrative embodiments thereof when considered in connection with the accompanying drawing wherein:

Fig. 1 illustrates vibratory motion of a free-free bar of the type involved in my invention.

Fig. 2 is a perspective view of a transducer arranged in accordance with my invention, together with a schematic and block diagram of a typical network connected thereto.

Figs. 3 and 4 illustrate modified forms of the transducer shown in Fig. 2.

Referring to the drawing, in Fig. 1 there is shown a free-free bar 10 comprising a flat elongated element supported at its center by a member 12 through which the bar 10 extends. It can be shown that, if either end of the bar 10 is struck or otherwise displaced (vertically, in the case of the bar shown in Fig. 1), the bar will vibrate in a pattern substantially as shown by the lines 14a, 14b. It can also be shown that frequency of vibration in the mode illustrated is given by the formula

$$f = \frac{3.116\pi}{l^2} \sqrt{\frac{QK^2}{\rho}}$$

where

l =length of the bar 10 in cm.

Q =Young's modulus in dynes/cm.

K =the radius of gyration of the bar section.

ρ =density of the bar in grams/cubic cm.

In accordance with my invention, the principle illustrated in Fig. 1 is utilized to provide a frequency sensitive sound wave transducer of simple construction.

Referring to Fig. 2, a sound wave transducer illustrating my invention comprises an electronic tube, having an evacuated metal envelope 16 provided with a base member 18, and with 40 prongs 20 in the base 18 for connecting the internal tube electrodes to an external circuit. A cathode electrode 22 is mounted within the envelope 16, and a free-free bar 10 extends through and is supported by the end wall 16a 45 of the tube envelope 16 so that one end 10a of the bar 10 is disposed within the tube envelope adjacent the cathode 22 to serve as an anode electrode, while the other end 10b of the bar 10 is disposed outside the tube envelope 16. 50 The line of support 10c for the bar 10 is approximately at the center thereof.

The cathode 22 may be either of the directly or indirectly heated type, supplied with heating current from a battery 24 or the like. For simplicity, no details are shown as to the manner

of heating or mounting the cathode 22 since such details are all well known in the electronic tube art. As shown, the tube envelope 16 is preferably made of metal to simplify electrical connection between the bar 10 and the tube envelope 16, although a glass envelope could be used if desired. The cathode and anode electrodes 22, 10a are preferably surrounded with a shield 28 connected to the cathode 22, to prevent current flow between the cathode 22 and the tube envelope 16.

A battery 28 or similar voltage source has one terminal connected to the tube envelope 16 (and, hence, to the anode 10a) through a load impedance 30, while the cathode 22 is connected to the other terminal of the battery 28 to establish space current flow between the cathode and anode.

As long as the ends 10a, 10b of the bar 10 are at rest, a uniform space current will flow from the cathode 22 to the anode 10a in the tube. However, if a sound wave having a frequency corresponding to the natural vibratory frequency (specified above) for the bar 10 impinges on the exposed end 10b of the bar, the exposed bar end 10b will vibrate in the manner illustrated in Fig. 1, with the vibrations induced by the sound wave being transmitted between the bar ends by mechanical coupling within the bar, with the result that the spacing between the anode 10a and the cathode 22 will vary, producing corresponding variations in the current flowing in the tube and in the load impedance 30. To detect the arrival of a sound wave, the impedance 30 can be connected through a capacitor 32 to an amplifier and detector 34 which will amplify and detect or rectify the fluctuating voltage developed across the load 30, and the resultant output of the amplifier-detector 34 can be utilized to actuate any suitable indicator 36, such as a meter or the like. In the case of modulated sound wave, the indicator 36 could be a headset, loudspeaker, or similar transducer.

It should be noted that the vibratory motion illustrated by the lines 14a, 14b in Fig. 1 is not strictly accurate as regards the conditions at the center of the bar. That is to say, although the free bar ends 10a, 10b will vibrate substantially in the manner shown, there will be little or no motion at the center of the bar. In this regard, an electronic tube constructed and operated in accordance with the invention represents a material improvement over prior art movable electrode tubes wherein one wall of the tube comprises a flexible diaphragm or other movable structure permitting transfer of mechanical motion through the tube wall. In my improved tube, it is only necessary that the tube envelope wall be sufficiently thin at the point of bar support so that the envelope wall will not interfere with or "damp" the motion of the bar on either side of the center thereof. For example, in a typical case, the free-free bar 10 may be 2.54 cm. long and .1 cm. in thickness, and the supporting wall of the tube approximately .2 cm. thick and approximately 1 cm. in diameter. The bar 10 may be composed of a material having a ratio

Q

¹

equal approximately to 3×10^{11} . Suitable materials are stainless steel, beryllium, or various aluminum alloys such as dural.

In the foregoing example, the frequency of maximum response for the transducer is approximately 26 kilocycles.

In Fig. 1, the bar 10 is shown as being flat rather than rectangular in shape. A flat bar is deemed preferable in many instances since its principle plane of vibration can be oriented readily to insure that the bar end 10a will always move toward and away from the cathode 22 rather than laterally with respect thereto, thus insuring maximum current change in the tube. At the same time, it will be understood that a flat bar will give the transducer a bidirectional response pattern with the plane of maximum response being at right angles to the bar face. If a more nearly omnidirectional response pattern is preferred, the bar can be made with a rectangular, circular, or other similar cross section, although the response pattern will still exhibit a slight maxima for sound waves arriving along a line through the cathode 22 and the bar anode 10a since motion of the bar end directly toward and away from the cathode 22 will cause greater current fluctuation than transverse displacement.

It is also to be understood that the invention is not limited to a diode-type tube, nor to the particular form of diode illustrated wherein the free bar end inside the tube serves as an anode, although the latter is the preferred arrangement in a diode type tube since it is somewhat inconvenient to heat the free bar end inside the tube as is necessary if the latter is to serve as a cathode. As for triode or other multi-electrode type tubes, the free bar end inside the tube can be used as an anode, as shown, or could as well be used as a movable current control grid, in a manner analogous to that shown in U. S. P. 1,569,684—Schwerlin, 2,290,531—Brett, or 2,165,981—Sampson. In any event, it will be seen that there are several ways in which a free-free bar can be used as a frequency sensitive element for transmitting mechanical motion through the envelope wall of an electronic tube in accordance with my invention.

The sensitivity of a transducer constructed in accordance with the invention can be increased by providing a baffle adjacent the exposed end of the free-free bar to decrease the adverse effects caused by a sound wave acting simultaneously on opposite surfaces of the exposed bar end. In Fig. 3, for example, I have shown the upper portion of a tube envelope 16 with one end 10b of a free-free bar extending therefrom. A generally U-shaped plate member 38 is mounted on the top of the tube envelope 16 adjacent to and coplanar with the free bar end 10b (when the latter is at rest). The baffle plate 38 effectively increases the free path distance between opposite faces of the free bar end 10b so that a sound wave impinging on one of the faces must travel an appreciable distance before reaching the opposite face and will, therefore, have less tendency to interfere with the vibrations originally set up in the bar 10.

Fig. 4 shows a slightly different type of baffle 38a in the general form of a longitudinal section of a cylinder partially enclosing the free bar end 10b. The form of baffle shown in Fig. 4 has the same effect as that shown in Fig. 3, with the additional feature that the transducer shown in Fig. 4 will be, for the most part, unresponsive to sound waves approaching the free bar end 10b on the enclosed side thereof. Accordingly, this type of baffle will provide a unidirectional transducer, and when mounted for pivotal movement about the longitudinal axis thereof, can be utili-

lized in sound wave direction finding equipment or the like.

I claim:

1. A sound wave transducer responsive to sound waves of predetermined frequency for generating alternating electrical currents corresponding in frequency to said predetermined frequency, said transducer comprising an evacuated envelope containing a plurality of electrodes for developing space current flow in said envelope, one of said electrodes comprising a vibratory free-free bar extending through a wall of said envelope and supported at its center by said wall so that one end of said bar is disposed outside of said envelope and the other end of said bar is disposed inside of said envelope in a position to alter said electron stream due to movement of said other bar end, said free-free bar comprising an elongated vibratory element supported approximately at its center and adapted to vibrate transversely at a frequency determined by the bar dimensions with a nodal point at the bar center and antinodal points at or near the bar ends when one bar end is set in motion transversely, the physical dimensions of said bar being such that said bar is mechanically vibratably resonant at said predetermined frequency.

2. In a sound wave transducer, a space discharge device comprising an envelope containing a plurality of electrodes for developing space current flow within said envelope, one of said electrodes comprising a vibratory free-free bar extending through a wall of said envelope and supported by said envelope wall intermediate the ends of said bar, said free-free bar comprising an elongated vibratory element supported approximately at its center and adapted to vibrate transversely at a frequency determined by the bar dimensions with a nodal point at the bar center and antinodal points at or near the bar ends when one bar end is set in motion transversely, said bar being vibrationally responsive to the impingement of sound waves of predetermined frequency on the free bar end outside of said envelope to cause the free bar end inside of said envelope to move with respect to another of said electrodes.

3. In a sound wave transducer as defined in claim 2, baffle means mounted on said envelope wall adjacent said free bar end outside of said envelope to increase the free space path from one side of said outside free bar end to a side opposite said one side.

4. In a sound wave transducer as defined in claim 2, baffle means mounted on said envelope wall adjacent to and partially surrounding said free bar end outside of said envelope to render said transducer predominantly responsive to sound waves approaching said device on the exposed side of said outside free bar end.

5. In a sound wave transducer, an electronic tube comprising an evacuated envelope containing a plurality of electrodes, one of said electrodes comprising a vibratory free-free bar ex-

tending through a wall of said envelope and supported by said envelope wall at the center said bar, said free-free bar comprising an elongated vibratory element supported approximately at its center and adapted to vibrate transversely at a frequency determined by the bar dimensions with a nodal point at the bar center and antinodal points at or near the bar ends when one bar end is set in motion transversely, said bar being vibrationally responsive to the impingement of sound waves of predetermined frequency on the free bar end outside of said envelope to cause the free bar end inside of said envelope to move with respect to another of said electrodes.

6. A vacuum tube comprising an evacuated envelope, a vibratory free-free bar extending through said envelope, said free-free bar comprising an elongated vibratory element supported approximately at its center and adapted to vibrate transversely at a frequency determined by the bar dimensions with a nodal point at the bar center and antinodal points at or near the bar ends when one bar end is set in motion transversely, a cathode electrode within said envelope, the free end of said bar inside of said envelope being adjacent to said cathode and constituting an anode electrode to cooperate with said cathode electrode in establishing space current flow within said envelope.

7. A sound wave transducer comprising an evacuated envelope, a vibratory free-free bar extending through one wall of said envelope and supported at its midpoint by said wall, said free-free bar comprising an elongated vibratory element supported approximately at its center and adapted to vibrate transversely at a frequency determined by the bar dimensions with a nodal point at the bar center and antinodal points at or near the bar ends when one bar end is set in motion transversely, the portion of said bar inside said envelope constituting a first electrode within said envelope, a second electrode rigidly mounted within said envelope to cooperate with said first electrode in establishing space current flow within said envelope, and a shielding electrode mounted within said envelope surrounding said first and second electrodes and connected to said second electrode.
